UNITED STATES PATENT OFFICE.

FREDERIC L. WANKLYN, OF MONTREAL, QUEBEC, CANADA.

TRACK-SIGNAL.

1,355,871.

Specification of Letters Patent. Patented Oct. 19, 1920.

Application filed March 18, 1920. Serial No. 387,018.

To all whom it may concern:

Be it known that I, FREDERIC L. WANKLYN, of the city of Montreal, county of Hochelaga, Province of Quebec, Dominion of Canada, a subject of the King of Great Britain, have invented certain new and useful Improvements in Track-Signals; and I do hereby declare that the following is a full, clear, and exact description thereof.

10 My invention relates particularly to detonating track torpedoes or fog signals for use on railways.

Heretofore devices of this nature have not been effective under certain conditions, as for instance, when the noise due to vibration has been too great for the engine driver to hear the detonation, and this invention has for its object to provide a torpedo or fog signal which will fulfil the requirements of a detonator and at the same time supplement the detonation by a brilliant flash and a pungent odor.

To this end the invention consists of a torpedo comprising a hermetically sealed water-proof container carrying a detonator and a charge of flash light and pungent odor producing powder, the container being provided with spring clips by which it may be readily attached to the rail head.

30 For full comprehension however of my invention reference must be had to the accompanying drawings in which similar reference characters indicate the same parts and wherein:

35 Figure 1 is a plan view of my improved invention;

Fig. 2 is a longitudinal sectional view taken on line 2—2 Fig. 1;

Fig. 3 is a transverse sectional view taken 40 on line 3—3 Fig. 2;

Fig. 4 is a detail view illustrating a modified form of my torpedo; and

45 Figs. 5 and 6 are under side views of the rectangular and circular torpedoes respectively.

Although my improved signaling appliance has the appearance of a torpedo it also performs the function of a signal flash-light and the elements of my signal device 50 may be contained in a rectangular container as illustrated in Fig. 1 or a container of circular form as illustrated in Fig. 6, and although the sections illustrated by Figs. 2 and 3 are indicated on the illustration of the rectangular container in Fig. 1

they are equally illustrative of similar sections of the circular container.

Each container is fastened in a carrier *b* consisting of a comparatively thin sheet metal, preferably tin coated or galvanized. 60 The charge consisting of a plastic cake *c* of any suitable detonating mixture and a flash powder *d* consisting of magnesium or a combination of potassium chlorate and magnesium. In order to obtain a pungent 65 odor a small quantity *e* of red arsenic or other inflammable substance capable of producing a pungent odor is added to the mixture.

These ingredients, the detonator—cake 70 and flash-light and odor producing powders are inclosed in a water-proof container consisting of a fibrous envelop which has been subjected to a suitable water-proofing treatment. This container is indicated at *f*, the 75 open ends of which are crimped within the turned-over edges *g* of the carrier. These ingredients may be charged into the container simultaneously or separately.

The ingredients of the detonating cake 80 must be such that sudden abrasion such as produced by the wheel of a locomotive passing over it while detonating it will instantaneously ignite the flash-light and odor producing powders thus producing a loud 85 detonation and at the same time a brilliant flash and simultaneously a pungent odor.

In order that the signal device may be held firmly in place notwithstanding the excessive vibration of the rail due to an approaching locomotive and at the same time the track be automatically cleared of the expended torpedo after it has performed its triple function, the thin sheet metal floor of the container has a pair of slots *k* and a 90 pair of spring clips formed from a strip *m* of resilient metal the middle portion of which has a pair of spaced crimps *n* and *o* registering with and protruding downwardly through the slots *k*, the strip lying 95 over the floor of the carrier and being secured thereto by a rivet *p*. These clips are made to conform in a measure to the average rail head and their resilience adapt them to fit different sizes and shapes of 100 heads; the ends of the clips being bent inwardly as at *r* to grip the lower portion of the head. When the locomotive wheel passes over this signal device the pressure breaks the resilient strip at one or both 110

crimps n and o and the device springs from the rail head.

What I claim is as follows:

- 5 1. A railway signaling appliance consisting of the combination with a container and means for fastening the same to a rail head of a detonator and a flash-light powder and inflammable powder producing a pungent odor on ignition.
- 10 2. A railway signaling appliance consisting of a carrier, a spring clip comprising a strip of resilient metal secured to the carrier and presenting an arch to rest on the top of the rail and downwardly extending
- 15 3. converging legs having inwardly and upwardly curved ends for gripping the sides of the rail-head, a container secured to the carrier and containing a detonator, and a flash-light powder.

3. A railway signaling appliance consisting of a carrier having parallel spaced slots, spring clips consisting of a strip of resilient metal secured to the carrier and having crimps registering with and protruding slightly through the slots; a water-proof 25 fibrous container secured in the carrier by crimped edges of the latter; and a detonator, a flash-light powder and inflammable powder producing a pungent odor on ignition, all contained within the container. 30

In testimony whereof I have signed my name to this specification in the presence of two witnesses.

FREDERIC L. WANKLYN.
